RAZOR BLADE MAGAZINE

Edward J. Gray, New York, N. Y.; Irene Carol Gray executrix of said Edward J. Gray, deceased

Application November 19, 1948, Serial No. 61,005

7 Claims. (Cl. 206—16)

1

This invention relates to razor blade magazines, more particularly to a magazine for dispensing conventional double edge safety razor blades.

It is among the objects of my invention to provide a magazine for double edge safety razor blades that is neat, compact, light in weight and simple and inexpensive to manufacture, having no moving parts that may jam or otherwise become out of order, that may readily be filled in the factory by mass production methods, or in the home by the user without the need for special tools or skill, and without danger of injury to the person, that retains a plurality of razor blades therein without the use of special springs or clamps, and holds such blades firmly in place yet ensures convenient and ready removal of only one blade at a time when desired, without danger of jamming thereof or of injury to the edge of the blade or the fingers of the user.

According to a feature, the stack of safety razor blades is maintained in bowed condition within the magazine, to act at all times as its own spring follower and by virtue of the resilience of the blades is at all times urged to proper registry for removal of the extreme blade of the stack from the blade discharge outlet of the magazine. In a preferred embodiment the magazine is composed of a base and a cover which may be snapped into closed position, the base having an upstanding or fulcrum element as an integral part thereof and areas of the cover depressing the ends of the blades to bend the latter over said fulcrum element into the desired bowed relation.

According to another feature, the magazine is provided with stop means coacting with the conventional slots of the blades to block against removal from the magazine all the blades of the stack other than the extreme blade which inherently is flexed to clear such stop, and further stop means is provided to coact with only the extreme blade and block its movement in direction away from its outlet.

According to another feature of the invention, the blades are interleaved in a stack from the opposite ends of which the outer ends of alternate blades protrude. Ejector means are provided, movable longitudinally with respect to said base alternately in opposite directions, with each stroke to engage the inner end edge of the topmost remaining blade adjacent the center of said base to slide such topmost blade from the discharge outlet toward which said ejector means is moved, said ejector means while advancing such topmost blade, riding on the top surface of the second blade from the top, over and beyond

2

the inner end edge of such second blade, and when moved in opposite direction engaging the inner end edge of such second blade to advance the latter from its associated discharge outlet, means being provided to urge the stack toward the ejector means so that the inner end edge of the topmost blade remaining in the magazine will always be in the path of the ejector means.

In a preferred embodiment of the invention, 10 the various features above recited are employed in conjunction, that is, the interleaved stack is maintained in flexed condition by an appropriate upstanding portion or fulcrum on the base and the cover of the magazine desirably constitutes 15 the instrumentality for engaging and depressing the ends of the respective blades.

According to another feature, while the base 20 when molded of plastic, may constitute an integral piece incorporating the upstanding or fulcrum portion as well as the blade stopping portion, the base when made of sheet metal desirably incorporates outstruck tongues to serve as the fulcrum piece or pieces, has separate stampings rising therefrom to serve as the blade stop means 25 for all but the topmost blade and the cover has outstruck means to serve as the stop for the topmost blade.

In the accompanying drawings in which is 30 shown one of various possible embodiments of the several features of the invention,

Fig. 1 is a plan view of the assembled device with parts broken away,

Fig. 2 is a bottom plan view of the assembled device,

Fig. 3 is a longitudinal sectional view taken 35 along line 3—3 of Fig. 1,

Fig. 4 is a view similar to Fig. 3 taken along line 4—4 of Fig. 1,

Fig. 5 is a sectional view taken along line 5—5 40 of Fig. 3,

Fig. 6 is a transverse sectional view taken along line 6—6 of Fig. 1,

Fig. 7 is a fragmentary view similar to Fig. 4 showing a blade being ejected, and,

Fig. 8 is an exploded perspective view of the 45 device showing the parts thereof.

Referring now to the drawings, as is clearly shown in Fig. 8, the device desirably comprises a housing having a base 11, and a cover 12. These parts are shown stamped from sheet metal although they may be molded from plastic.

The base 11 which includes a substantially rectangular bottom plate 15 of width greater than that of a conventional double edge safety razor 55 blade has upstanding means thereon to serve as

a fulcrum, which in the sheet metal embodiment shown may comprise a pair of transversely aligned upstanding spring tongues 16, 17 and 16', 17' struck out therefrom on each side respectively of a line extending transversely across the center of the bottom plate 15, the width of each pair of spring tongues being less than the width of a conventional double edge safety razor blade. The pairs of spring tongues respectively extend upwardly from said bottom plate 15 at an acute angle thereto toward each end 18 and 19 thereof. As shown in Fig. 8, an opening 21 is formed in the bottom plate by the struckout spring tongues and a longitudinal slot 22 is provided in the bottom plate between the spring tongues of each of said pairs.

Formed integrally with the bottom plate 15 along each of the side edges 23 and 24 thereof is an upstanding wall 25 which has an inclined notch 26 at each corner thereof, respectively, extending downwardly toward the ends 18 and 19 of the bottom plate, said ends 18 and 19 each having an inclined lip portion 27 integral therewith and extending upwardly therefrom, the center of each of said lip portions being slightly raised as at 28.

The cover 12 which substantially conforms in shape to base 11 comprises a substantially rectangular top plate 41 substantially the same length as bottom plate 15 but slightly wider than the latter. Plate 41 preferably has a longitudinal central slot 42 therein in which is securely yet slidably positioned an ejector member or stud 43 headed at its top and bottom end as at 44 and 45 respectively. Preferably on each side of said slot, a pair of substantially L-shaped openings 46 are formed, the corners 47 of each of said openings being bent downwardly to form a stop for the razor blades in the manner hereinafter described.

The top plate 41 has a depending side wall 49 along each of the edges thereof, each of said walls desirably having an opening 51 centrally located therein, which when the cover is placed on the base with the side walls 49 of the former straddling the side walls 25 of the latter, will coat with a boss 52 on the side walls 25 of the base securely yet removably to retain the cover thereon.

Each corner of walls 49 of the top plate 41 has an inclined notch 53 therein extending downwardly toward the ends 54 and 55 respectively of the top plate 41, the associated notches 53, 26 in the cover 12 and the base 11 being aligned when the two are joined as above described. Each of the ends 54, 55 of the top plate 41 has a downwardly inclined lip portion 57 integral therewith, with the center of each of said lip portions being slightly depressed as at 58 and aligned with the raised portion 28 of lip 27, the width of such portions 28, 58 being less than the width of a conventional safety razor blade.

Associated with the base is an upstanding guide and stop member which extends through the longitudinal slots in the blades and blocks outward movement of all but the extreme blade. In the particular sheet metal embodiment herein shown the guide comprises a pair of razor blade guide members 13 and 14 which are identical, each comprising a substantially rectangular plate 31 having an upstanding side wall or guide 32 along one edge thereof slightly less in length than the plate 31 and substantially equal to the longitudinal length of the opening 21 formed in bottom plate 15 by the struckout tongues 75

thereof. Each of the ends 33 of the guide 32 is beveled and the upper edge 34 has a pair of spaced notches 35 and 36 therein. A spring finger 37 is struck out at each end of the plate 31 between the lateral edges thereof and bent upwardly as shown. Thus when the members 13 and 14 are placed in juxtaposition with their side walls or guides 32 against each other and inserted into the slot 22 formed between said spring tongues, the spring fingers 37 will pass into the opening 21 and snap over the edges 38 thereof, securely to retain the members 13 and 14 in place with their respective side walls or guides 32 in upright position.

To load the magazine, a conventional double edged razor blade 61 as shown in Fig. 3 is positioned on spring tongues 16' and 17' with end portion 62 of the blade positioned in notches 35 of the guide and stop member 13, 14 and with the guides 32 extending through the longitudinal slot 63 in the blade 61, in which position the other end 64 of the blade will extend toward the right beyond tongues 16', 17' and over inclined lip 27 of the base. A second blade 65 is then positioned on tongues 16, 17 with end 66 of the blade positioned in notches 36 and with the guides 32 extending through the longitudinal slot 63 in such blade, in which position the other end 68 of the blade will extend toward the left beyond tongues 16, 17 and over inclined lip 27 at the other end of base.

This stacking procedure is repeated until the desired number of blades are in the magazine in interleaved relation as shown in Figs. 3 and 4 with the outer end edges of alternate blades protruding at opposite ends of the stack.

The cover 12 is then positioned over the base 11 so that the side walls of the latter are straddled by the side walls of the former and the cover forced down until bosses 52 and openings 51 coat to lock the cover on the base.

With the cover in place, the cutting edges of the blades will be retained by guide and stop 13, 14 spaced from the side walls 25, 49 and the depressed portion 58 of the lips at each end thereof will press down on the outer ends of the blades as shown at 71 and 72 in Fig. 3, thereby exerting tension on and depressing such blades and bending them over the associated fulcrums, in the embodiment shown, the pairs of spring tongues 16, 17 and 16', 17', which are thereby bent downward and act as resilient fulcrums. Thus the other ends of the blades in the associated notches 35 and 36 will be urged upwards. However the height of the side walls 32 of the guide members and the depth of the notches 35 and 36 are such that only the end 76 of the topmost blade 73 will move out of notch 36 and will abut against the underface of the cover, thereby limiting the movement of the blades and securely retaining them in place by reason of their tensed condition caused by the bending thereof. Were the fulcrums rigid, it would not be possible to enclose as many blades in a magazine of given height as is possible with resilient fulcrums such as the spring tongues 16, 17 and 16', 17'. No matter how many blades are stacked in the magazine up to the limit of its capacity, they will with such resilient fulcrum, always be urged toward the cover 12 and hence there is assurance that the blades will always be securely retained in place.

To remove a blade it is merely necessary to slide stud 43 to the end of slot 42 from the position shown in full lines in Fig. 3 to the position

shown in dot and dash lines. During the movement of stud 43, the bottom head 45 thereof will engage the inner end edge 76 of the blade 73 and move the latter forward, head 45 riding on the top surface of blade 81 immediately below blade 73 and passing over the inner end edge 80 of blade 81. As the inner end edge 76 of the bowed blade 73 is against the underside of the top cover and out of notch 36, it will be pushed forward and out of the magazine through the 10 outlet formed between lips 25 and 57 as shown in Fig. 7.

As the blade advances through such outlet, it will gradually straighten out and the tension created by the bowing of such blade will also be 15 reduced so that the end of the blade protruding from the outlet may be grasped by the fingers of the user and readily be pulled from such outlet.

No great care need be exercised to keep the blade from lateral deflection as it is manually withdrawn after it reaches the position shown in Fig. 7 which might cause the cutting edges of the blade to rub against the walls of the base with resultant injury to the blade, since the cutting edges thereof would clear the casing at 25 aligned notches 26, 53.

As the portions 28 and 58 are narrower than the width of a blade, they will not touch the cutting edges thereof as the latter is withdrawn from the magazine and hence will not dull the 30 same.

It is to be noted that inasmuch as the ends of the blades beneath the topmost blade are in the associated notches 35, 36 as blade 73 is advanced the other blades will be restrained from longitudinal displacement and when the end 76 of blade 73 has moved past the end 80 of the blade 81 immediately therebelow under the urging of stud 43, such end 80 by reason of the bowing of blade 81 will rise out of notch 35 until restrained by the underside of cover 12. To eject blade 81 the user then need merely move stud 43 in reverse direction and as the head 45 thereof engages end 80 of blade 81 it will move the latter from the outlet formed by lips 25 and 57 at the other end of the housing in the manner previously described with respect to blade 73. By repeating this procedure, successive blades may alternately be removed from the outlets at the ends of the magazine. This is true even if the ejector head 45 were of thickness greater than the thickness of a blade since any excess thickness of such head 45 would simply correspondingly depress the stack beneath the topmost blade without any affect on the operation of the device.

As the head 45 of stud 43 will slide over the end of the blade in the stack immediately below blade 73, it can only abut against the end of the topmost blade and accordingly but one blade can be removed at a time with no danger of jamming.

If in initially loading the magazine, the stud 43 should be in the position shown in dot and dash lines in Fig. 3, it would first have to be moved to the right to the position shown in full lines, before the topmost blade 73 could be removed as heretofore set forth. As blade 73 will have the notched corners 73' of its rear end 76 against inturned corners 47 the blade cannot be moved longitudinally to the right by the frictional engagement of head 45 of stud 43 against the face of the topmost blade in the stack which might advance the topmost blade so that its rear end 76 extends beyond the extreme position of

head 45 of the stud, thereby preventing the head from engaging end 76 of the blade for ejection thereof.

While for all the foregoing reasons the interleaved arrangement is preferred, it is however within the scope of the invention from its broader aspect to have the blades vertically aligned, either bowed or flat, and have the ejection thereof through one and the same opening. In such case the ejector head 45 must be no greater in thickness than the thickness of a blade so that it would only engage the end of one blade at a time. This construction is of course more delicate and requires more precision than that of the embodiment illustratively shown herein.

The magazine herein described is light in weight, simple to use and as it may readily be stamped from sheet metal, is relatively inexpensive and may be discarded after the blades therein are exhausted. Even with wet hands, a blade may readily be removed therefrom and the inconvenience and difficulty incurred in removing the wrapping from paper covered blades is dispensed with.

As many changes could be made in the above construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters 35 Patent of the United States is:

1. As an article of manufacture, a magazine for a plurality of stacked resilient safety razor blades of the type having a longitudinal slot therein, said magazine comprising a substantially 40 rectangular base having an upwardly inclined lip at each end thereof, a pair of upstanding spring tongues struck out from said base on each side of the center line thereof, said base having a longitudinal slot extending between each of 45 said pairs of spring tongues, upstanding guide means on said base positioned between said pair of spring tongues and extending through the longitudinal slot therebetween, and adapted to coact with the longitudinal slots in such blades to position the latter on said base in interleaved relation with the outer ends of alternate blades protruding from opposite ends of such stack, a substantially rectangular cover member having a downwardly inclined lip portion at each end 50 thereof, means to affix said cover member to said base with the lip portions on said cover spaced from the lip portions on said base whereby when said magazine is loaded said lip portions on said cover will depress the associated ends of such blades to bow the latter over said spring tongues and raise the free ends of such blades against the mid portion of said cover member and ejector means 55 movable longitudinally with respect to said cover member, alternately in opposite directions with each stroke, against the end of the topmost blade nearest the mid portion of said cover member to eject such topmost blade from between the spaced lip portions at the end of the magazine toward which said ejector means 60 is moving.

2. The combination set forth in claim 1 in which the ejector means to slide such blades comprises a vertical stud slidably positioned in a longitudinal slot in said cover, whereby when 65 said stud is moved longitudinally of said cover,

the lower end thereof will abut against an end of the topmost blade of such stack to move the latter out of said magazine between the spaced lip portions at the ends thereof.

3. The combination set forth in claim 1 in which the lip portions of said cover each has a depressed portion in the center thereof and the lip portions of said base each has a raised portion in the center thereof aligned respectively with the depressed portions on said cover. 10

4. The combination set forth in claim 1 in which means are provided on said cover adjacent the center thereof to block longitudinal displacement of the topmost razor blade away from its outlet.

5. The combination set forth in claim 1 in which said upstanding guide means comprises a pair of L-shaped members each comprising a base portion having an upstanding wall along one edge thereof, said wall having a pair of notches in the upper edge thereof, said base portion having means thereon securely to affix said guide means to the base of said magazine with said upstanding walls parallel to each other. 20

6. The combination set forth in claim 1 in which said base has an upstanding wall and said

cover has a depending wall along each of the longitudinal edges thereof and means are provided on said walls of said cover and said base securely to hold the two together. 8

7. The combination set forth in claim 6 in which each of said cover walls and base walls has an inclined notch in each corner thereof with associated notches in said cover walls and said base walls being aligned.

EDWARD J. GRAY.
